Primary Examiner — Katrina A Betton*(74) Attorney, Agent, or Firm* — Mauriel Kapouytian
Woods LLP; Benjamin Charkow(57) CLAIM

The ornamental design for a strap, as shown and described.

DESCRIPTION

FIG. 1 is a perspective view of a strap;
FIG. 2 is a bottom plan view of the strap of FIG. 1;
FIG. 3 is a top plan view of the strap of FIG. 1;
FIG. 4 is a left side view of the strap of FIG. 1;
FIG. 5 is a right side view of the strap of FIG. 1;
FIG. 6 is a front view of the strap of FIG. 1, the rear view appearing the same;
FIG. 7 is a perspective view of another exemplary embodiment of the strap of FIG. 1.

The portion(s) of the strap shown in broken lines are for environmental purposes only and do not form part of the claimed design. In the drawings the broken lines in FIG. 7 depict a seat back and form no part of the claimed design.
